UNITED STATES PATENT OFFICE.

ROBERT B. SMITH, OF QUINCY, MASSACHUSETTS, ASSIGNOR TO UNITED SHOE MACHINERY COMPANY, OF PATERSON, NEW JERSEY, A CORPORATION OF NEW JERSEY.

EYELETING-MACHINE.

No. 926,903.

Specification of Letters Patent.

Patented July 6, 1909.

Application filed August 27, 1906. Serial No. 332,158.

To all whom it may concern:

Be it known that I, ROBERT B. SMITH, a citizen of the United States, residing at Quincy, in the county of Norfolk and Commonwealth of Massachusetts, have invented certain Improvements in Eyeletting - Machines, of which the following description, in connection with the accompanying drawings, is a specification, like reference characters on the drawings indicating like parts in the several figures.

This invention relates to eyeletting machines, and pertains more particularly to those elements which guide the work while it is being fed, and which contribute to maintain the work in proper position when it is at rest.

The invention is particularly applicable to work-controlling devices such as are described in a co-pending application for Letters Patent of the United States, Serial No. 329,722, filed August 8, 1906; and the invention is intended primarily to supply improvements upon the subject matter of said co-pending application. Nothing herein contained is to be construed, however, as limiting this invention to use in connection with the devices shown and described in said application, or in connection with devices of the same type.

Commonly the work-controlling means of an eyeletting machine comprises coöperating surfaces which act upon opposite faces of the work. In some types of work-controlling means heretofore used one of the coöperating surfaces is supplied by a stationary guide-plate, the other being carried on an intermittently acting clamping member which clamps the work against the guide-plate when the former is at rest and which retreats from its clamping position to permit the work to be fed. This intermittent clamping action is disadvantageous, since it requires that the work be controlled manually by the operator whenever the clamping member retreats from engagement with the work, and also for other reasons unnecessary to be discussed herein. The improvements described in said co-pending application remedy the defects of the intermittent action of the work-controlling means just referred to, by providing, in an eyeletting machine, work-controlling means constantly acting upon the work to hold it in correct position when it is at rest and to guide it when in motion.

Viewed from another standpoint, certain

types of work-controlling means heretofore employed comprise each a stationary guide-plate, and a pair of clamping surfaces which co-act to hold the work against the guide-plate, said surfaces being commonly supplied by two substantially parallel fingers disposed on opposite sides of the eyelet-setting die of the machine, and extending from said die in a reverse direction to that in which the stock is fed. Thus the clamping surfaces which act on the work are spaced apart a considerable distance, and that area of the work which intervenes between them is not subjected to immediate control except insofar as it is controlled manually by the operator. With this arrangement the work-controlling means are ineffective to keep the work smooth and to insure its introduction in proper condition to the eyelet-setting operation. These deficiencies are remedied by the improvements described in the aforementioned co-pending application which comprise work-controlling means arranged for engaging the work along a continuous line which extends across the path traversed by the work as it is fed toward an eyelet-setting position. By this arrangement the work is smoothed out by the work-controlling means, and is held smooth while an eyelet is set.

Evidently, it is greatly to be preferred both that the work-controlling means constantly exert an active influence on the work, and that this influence be exerted through engagement along a continuous line extending across the path traversed by the work as it is fed toward an eyelet-setting position. These preferences may be supplied advantageously by the improvements described in the aforementioned co-pending application and said improvements are capable of successful operation under nearly all of the varying conditions of eyeletting. In some instances, however, the work may carry a projection of some sort (a lacing hook or stud, for example); and if it be desired to set an eyelet near said projection it may become necessary that the work-controlling means engage the work in the vicinity of said projection in such a manner that, when the work has reached its intended position, the projection might lie between the coöperating faces of the work-controlling means or within the area in which they are designed to contact with the work. In such a case the devices shown in the drawings of said

co-pending application would prevent the feeding of the work to the desired position because the projection would strike against the work-controlling means and could not 5 practicably be positioned within their intended area of contact; and in another type of work-controlling means hitherto employed, while the work might be fed to the desired position, the coöperating surfaces of 10 the work-controlling means would be prevented from coming close enough together to attain effective contact with the work.

The occurrence of a projection which might give rise to the difficulties just suggested is well exemplified in the operation 15 of setting eyelets in a shoe fly which has been provided previously with "blind hooks." In "blind hook" work lacing hooks are set in a shoe fly by projecting their barrels, or other 20 fastening means, through each fly of the shoe and usually through a reinforcement on the inside of the fly, and clinching said barrels against the inner face of said reinforcement. Thereupon a front facing (usu- 25 ally consisting of a narrow strip of soft leather) is stitched to the edge of the fly from one end to the other thereof, so as to cover the clenched ends of the hook barrels and afford a reinforced backing for the eye- 30 lets. The upper thus prepared is ready for the eyeleting operation. Obviously the lacing passage of the eyelet should extend entirely through the fly and the facing, and hence eyelets are set subsequently to the 35 hook setting operation and after the facing has been stitched in place. It is a frequent custom to commence setting eyelets at the lowermost end of a shoe fly and to set them in a row ending in proximity to the lower- 40 most lacing hook. In order that the last eyelet shall be properly positioned as close to the lowermost hook as desired, it may be necessary for the work-controlling means to engage between coöperating surfaces that 45 portion of the work in which the lowermost hook is located. It might be possible to set an eyelet as close as desired to a projection on the work, by employing work-controlling means comprising a guide-plate and a pair 50 of co-acting fingers (already referred to), the space intervening between the fingers affording an uninterrupted path through which the projection might be moved toward the eyelet-setting die; but the attain- 55 ment of this advantage in this manner would involve a permanent sacrifice of continuity of engagement, between work-controlling means and work, along a line extending across the path traversed by the work as it is 60 fed toward the die.

An important feature of this invention consists in work-controlling means which constantly engage the work, said work-controlling means being constructed and 65 arranged for permitting a projection on the

work to be positioned as near as desired to the eyelet-setting point.

Another feature of the invention consists in work-controlling means which normally engage the work along a continuous line extending across the path traversed by the work as it approaches an eyeleting position, and provision for interrupting the continuity of said engagement. In this manner the invention provides work-controlling means 75 which have all the desirable attributes, without the permanent disadvantages, of the arrangement of guide-plate and co-acting fingers already discussed.

The invention also comprises work-controlling means having coöperating surfaces arranged to press the work between them; said work-controlling means being arranged for distributing pressure substantially uniformly throughout the contact between said surfaces and the work. In work-controlling means heretofore used, abnormal thicknesses of leather, a thick line of stitching or the like, upon entering into engagement with the work-controlling means, has been likely 80 to cause the pressure of said means to be distributed unequally upon the work, thereby giving rise to difficulties hereinafter explained. This feature of the invention obviates these difficulties. 85

Other features of the invention will be described herein and will be defined in the claims.

One embodiment of this invention may be used to advantage on a machine arranged 100 to set two eyelets simultaneously in the opposite flies of a shoe. Such a machine is shown and described in Letters Patent of the United States, No. 683,488, dated October 1, 1901, and a similar machine 105 having improvements over the machine of said patent is shown in a co-pending application for Letters Patent of the United States, Serial No. 153,822, filed April 22, 1903. The present invention will be described herein, 110 for purposes of illustration, as applicable to a machine of this type, and as embodied in work-controlling means somewhat similar to those shown in the drawings of the aforementioned co-pending application Serial No. 115 329,722. Nothing herein contained is to be construed as limiting this invention to use in connection with the machines of said patent, or to machines of that general type, since the invention may be applied to many 120 sorts of eyeleting machines and to machines for setting other fasteners than eyelets.

In the accompanying drawings, Figure 1 is a top view of work-controlling means embodying this invention, showing them in 125 their association with an anvil-plate; Fig. 2 is a side elevation of the work-controlling means shown in Fig. 1, illustrating the manner of introducing the two flies of a shoe; Fig. 3 is a side view of a portion of the 130

work-controlling means showing the relative positions of certain parts when a piece of work has been introduced; Fig. 4 is a top view, similar to Fig. 1, showing the relation 5 between the work-controlling means and the anvil-plate when the latter is in position for setting an eyelet; Fig. 5 is a view similar to Fig. 4 showing the relative positions of work-controlling means and anvil-plate when 10 the latter has been shifted to feed the work; Fig. 6 is a section along the line 6—6 of Fig. 4, showing a piece of work carrying a lacing hook; Fig. 7 is a section similar to that of Fig. 6 showing a piece of work 15 carrying a lacing hook in another position; Fig. 8 is a section along the line 8—8 of Fig. 1. Figs. 2 and 3 are full size. Figs. 1, 2, and 5 are approximately three-fourths size. Figs. 6, 7 and 8 are drawn to the scale 20 of two to one.

Fig. 1 shows enough of an eyeletting machine, of the type described specifically in said application, Serial No. 153,822, to exemplify the use of work-controlling means 25 embodying this invention. An anvil-plate *a* is pivotally supported on a stud *b* which is arranged to be moved laterally forward and backward to give the anvil-plate the positions shown in Figs. 1 and 4. The anvil-plate *a* is arranged to be rocked on the stud *b* for the purpose of feeding the work. During the operation of the machine of said application, Serial No. 153,822, an anvil-plate substantially like the plate *a* is moved to 30 three successive positions, and for the purposes of the following detailed description the anvil-plate *a* may be understood to be moved in the same manner and to the same end. The three positions of the anvil-plate 35 *a* (named in the sequence in which they are assumed) are the hole-punching position shown in Fig. 1; the eyelet-setting position shown in Fig. 4; and the extreme feeding position shown in Fig. 5. The punching position (Fig. 1) is the initial position of the anvil-plate in the cycle of operations of the machine. The path of movement of the anvil-plate is represented diagrammatically in Fig. 5 by the lines 10, 11, and 12. The anvil-plate *a* carries a punch-anvil *c* and a setting-die *d* which are duplicated on the under side of the anvil-plate as viewed in Figs. 1, 4 and 5. In the manner described in said application, Serial No. 153,822, oppositely 40 disposed punches may be provided in axial alignment with each other and with the punch-anvils. In like manner oppositely disposed pressure-dies may be provided to coöperate with the setting-dies *d*, *d*. It is 45 unnecessary to show in the present drawings these punches and pressure-dies since the manner of their coöperation with an anvil-plate like the plate *a* is sufficiently elucidated in said application, Serial No. 153,822. 50 The work-controlling means comprise a

normally stationary guide-plate *A* and oppositely disposed presser-feet *B*, *B*. The guide-plate is mounted on a bracket 13 projecting from the frame 14 of the machine. As shown in Fig. 1 the guide-plate *A* is arranged to be reciprocated endwise on the bracket 13 for spacing eyelets at different distances from the edge of the work, and to this end the guide-plate is slidable on the bracket 13 and has a rigid rack 15 engaging 70 with a toothed sector 16 which may constitute an instrumentality of an automatic spacing mechanism such as is shown in said application, Serial No. 153,822. In introducing work to the work-controlling means, 75 the two flies of a shoe are preferably arranged by the operator so as to be substantially parallel with their edges registering, and are then inserted between the guide-plate *A* and the respective presser-feet *B*, *B* 80 (see flies *e*, *e* Fig. 2). When in complete engagement with the work-controlling means each fly *e* occupies a position similar to that shown in Fig. 3, with its edge abutting against an edge-gage *i*. 85

When the two flies *e*, *e* are in position, one of them will lie above and the other beneath the anvil-plate *a* which will be in the position shown in Fig. 1. The first step in the operation of the machine is performed by 90 the punches which are pressed through the work against the oppositely disposed punch-anvils *c*; and are then retreated, leaving a hole for an eyelet in each fly. Thereupon the anvil-plate is moved in the direction of 95 the line 10 (Fig. 5) to the position shown in Fig. 4, wherein each setting-die *d* registers with a hole in the work just made by a punch. An eyelet is introduced into each of said holes and the oppositely disposed pressure-dies 100 (not shown) are caused to press the eyelets so as to upset their barrels upon the dies *d*, *d*. While the pressure-dies and the upsetting-dies *d*, *d* still engage the newly set eyelets between them, (the pressure of said engagement having been slightly reduced) the anvil-plate and the pressure-dies are moved simultaneously in the direction of the line 105 11 until the anvil-plate reaches the position shown in Fig. 5, thereby feeding the work 110 115 for the distance desired to intervene between two eyelets. When the anvil-plate has reached the position shown in Fig. 5 the pressure-dies are retreated to release the work and the anvil-plate is thereupon 120 returned (along the line 12) to its initial position shown in Fig. 1 wherein the punch-anvil *c* registers with that portion of the work in which it is desired to punch a hole for the next eyelet. This completes one cycle of the 125 operation of the machine insofar as it is necessary to be considered in the present discussion.

The presser-feet *B*, *B* are supported by leaf-springs *f*, *f*, secured to opposite sides of a 130

block 17. Said block is recessed to fit over the shank of the guide-plate A and is held in position thereon by a set-screw 18 which may project through an elongated slot in the block for purposes of adjustment. The front faces of the block 17 supply the edge-gages *i* against which the edges of the work move and are positioned. Each presser-foot carries a centrally located pivot *g* which is conveniently supplied by the end of a hooked plate *h*. This pivot is seated upon the outer end of the appropriate spring *f* which is given a proper shape to suit this purpose. Each spring *f* tends to press the presser-foot to which it is attached toward the guide-plate A and to hold it thereagainst firmly but with a yielding pressure, and to this end the outer extremity of the spring *f* is preferably confined between the pivot *g* and the body portion of the presser-foot (see Fig. 2). The purpose of this pivotal support for each presser-foot is to enable the foot to conform to inequalities in thickness of the work and to distribute the pressure of the spring *f* uniformly to all parts of the work with which the foot contacts. The behavior of the presser-feet when moved on their pivots is illustrated in Fig. 2 where pieces of work are being introduced beneath the presser-feet. It is evident that the pressure exerted on the edge of the work by one end of a presser-foot in Fig. 2 is substantially the same as the pressure exerted by the other end of the presser-foot; and the same would be true if a piece of work of varying thickness were in engagement with the presser-foot. Fig. 3 shows a piece of work of uniform thickness in engagement with the presser-foot which is, under these conditions, substantially parallel to the guide-plate. If the thickness of one part or another of the work in this instance were abnormal the presser-foot would be rocked somewhat out of parallel, but would nevertheless transmit pressure uniformly to the work. Each spring *f* is maintained in proper alinement by guide-pins 19 and 20 carried respectively by the block 17 and the appropriate presser-foot. The uniformity of the pressure on the work exerted by each presser-foot is of importance since it enables the work-controlling means to exert the same influence on all parts of the work engaged thereby. In work-controlling means heretofore used, an abnormal thickness of work, a thick line of stitching, or the like, was likely to increase the pressure in its own vicinity and to diminish the pressure at other parts of the work, so that some portions of the work would be engaged more securely than others, thereby permitting the stock to be easily wrinkled and lowering the efficiency of the work-controlling means. It should be noted that the work-controlling means shown in the drawings are normally stationary, the

presser-feet being moved only under unusual conditions or when work is being introduced.

In order to permit a projection on the work, such as a lacing hook, to be moved near to the setting point, each presser-foot is provided with a laterally-extending recess C, which for a certain distance supplies an uninterrupted path along which the projection may be moved toward the setting point. This may be explained conveniently in connection with Figs. 6 and 7, wherein a lacing hook D is shown positioned within the recess C. If this recess C were not provided the hook D, moving in the direction of feed of the work (see arrow 21), could approach no nearer to the setting point (above the die *d*) than the side 22 of the presser-foot, since the hook would abut against said side during the feed. The provision of said recess, however, permits a projection on the work to be moved from one side toward the other of the work-controlling means, and permits a projection on the work to be positioned between one side and the other of the work-controlling means, and permits a projection on the work to be moved from the rear side of the work-controlling means toward the setting point, the expression "rear side" being used to designate that side of the work-controlling means which is first reached by the work in its feeding movement.

The forward end of each recess C may be provided with a spring-gate E. This gate is secured to the presser-foot preferably by a pivot and is maintained normally closed as shown in Fig. 6 by means of a spring-actuated plunger F carried in a socket in the presser-foot. The gate is preferably arranged to open outwardly only. It may be opened thus, against the action of the spring-pressed plunger, by a projection on the work as exemplified by a lacing hook D in Fig. 7. When the gate E is in its normal vertical position the edge of the gate is substantially flush with the acting surface of the presser-foot; and consequently the presser-foot is normally arranged to engage the work along a continuous line extending across the path traversed by the work as it is fed toward the setting-point, and the gate constitutes an illustration of provision for interrupting the continuity of said engagement to permit a projection on the work to be positioned as near as desired to the setting-point. The opposite faces of the guide-plate A are provided with projecting ribs *j* (similar to those shown in the aforementioned co-pending application) which coöperate with the presser-feet B, B to maintain the edges of the work in contact with the edge-gages *i*, *i*.

It is desirable, for some classes of work, to provide a guide-plate with a work-rest against which the operator may hold the work in proper position when it is desired to set an

eyelet so near to the rear end of the work that the work-controlling means are not permitted effective engagement with the work. In this connection the present drawings show a 5 work-rest G which projects laterally from the outer end of the guide-plate A. Work-rests somewhat similar to that shown in the drawings have been provided heretofore, and it has been experienced that some loose portion 10 of a shoe, such as the tongue, a part of the lining or the like, has been likely to drop down between the anvil-plate and the work-rest and to be pinched therebetween during the movement of the anvil-plate returning to 15 its initial position after the work has been fed. This impedes the feed of the work, and in many instances causes a hole to be punched and an eyelet set at a wrong place on the work. In order to avoid this difficulty and 20 to prevent any portion of the work from being pinched by the anvil-plate, this invention contemplates an arrangement of the anvil-plate and rest whereby the acting surfaces of both are rendered substantially continuous 25 when one is being moved toward the other, thereby preventing the occurrence of a space between them into which a part of the work could fall and be pinched. In this connection the present drawings show a recess H 30 (see Figs. 4 and 8) into which the lower end of the anvil-plate projects during a part of its travel in the direction of the line 12 (see Fig. 5). Each acting surface of the anvil-plate, with this arrangement, becomes substantially 35 a continuation of the adjacent face of the work-rest at a time when it is desired that no space intervene between adjacent portions of the anvil-plate and work-rest.

Many changes might be made in the devices shown in the drawings. For example, the work-controlling means may be used in connection with anvil-plates or the like which are entirely dissimilar, both as to construction and mode of operation, to the anvil-45 plate shown in the drawings. It is by no means necessary that the work-controlling means comprise coöperating surfaces one of which is stationary, as by being supplied upon a stationary guide-plate. It is preferred that the presser - feet be supported yieldingly but this is not essential. The provision of the recess C is not necessarily supplied by a recess in an integral block but may be supplied between two or more separate 55 parts which may be independent. The form and arrangement of the provision for interrupting the continuity of engagement between work and presser - foot might be changed in many ways and the gate shown 60 and described herein is merely a preferred form.

While it is preferred to employ all of the features of this invention conjointly as in the case of the devices shown in the drawings,

the features may be employed severally in 65 various connections. The features of the invention both collectively and severally are capable of application to eyeleting machines of different sorts and also to machines for setting other fasteners than eyelets. 70

All modifications such as have been suggested above, and the use of any feature or features of this invention in the connections just suggested, are to be construed as included within the proper scope of this invention as it is defined in the subjoined claims. 75

Having described my invention, what I claim as new and desire to secure by Letters Patent of the United States is:— 80

1. In an eyeleting machine, the combination with eyelet-setting devices, of means for feeding the work, work-controlling means extending transversely to the direction of feed for constantly engaging the work, said 85 means being constructed and arranged whereby projections on the work may be brought close to said eyelet-setting devices and also to engage the work for substantially its entire width. 90

2. In an eyeleting machine, the combination with eyelet-setting devices, of means for feeding the work, and work-controlling means extending transversely to the direction of feed for constantly engaging the work, 95 said latter means being constructed and arranged to engage the work for substantially its whole width and also to permit work having projections to be moved from one side of said means toward the other. 100

3. In an eyeleting machine, the combination with eyelet setting devices, of a guide plate, means for feeding the work and a presser foot extending transversely to the direction of feed provided with means for permitting projections on the work to be moved from one side thereof toward the other, the said presser foot being constructed and arranged to exert pressure on the work for substantially its whole width. 105 110

4. In an eyeleting machine, the combination with work feeding devices, of a guide-plate, and a presser-foot extending transversely to the line of feed which constantly engages the work, said presser-foot being 115 constructed and arranged to engage the work for substantially its whole width and also to permit work having projections to be moved from one side of the presser-foot toward the other. 120

5. In an eyeleting machine, the combination with eyelet-setting devices, of a guide-plate, a presser-foot having a recess adjacent to said guide-plate, and a yielding gate extending across said recess. 125

6. In an eyeleting machine, the combination with eyelet-setting devices, of a guide-plate for guiding the work on opposite sides

thereof, and yielding presser-feet arranged to keep two marginal portions of the work respectively in contact with said guide-plate, each of the presser-feet having a recess adjacent to said guide-plate, and each being provided with a yielding gate extending across said recess.

7. In an eyeleting machine, the combination with work feeding devices, of work-controlling means extending transversely to the line of feed for constantly engaging the work, said means being constructed and arranged for distributing pressure substantially uniformly throughout the entire width thereof and for permitting the projections on the work to be moved from one side thereof toward the other.

8. In an eyeleting machine, the combination with eyelet-setting devices, of a guide-plate, a presser-foot provided with means for permitting projections on the work to be moved from one side thereof toward the other, said presser foot being provided with means for exerting pressure along substantially its whole width, and a spring support to which said presser-foot is pivotally attached.

9. In an eyeleting machine, the combination with eyelet-setting devices, of a guide-plate, a work-rest extending from said guide plate, an anvil-plate, and means for moving said work rest and anvil plate relatively to each other, the work rest and anvil plate be-

ing arranged to form a substantially continuous surface when the relative movement 35 brings them near each other.

10. In an eyeleting machine, the combination with eyelet-setting devices, of an anvil-plate, a guide-plate, and a work-rest extending laterally from the said guide-plate and 40 having a recess for receiving a portion of the anvil-plate.

11. In a machine for operating on boots and shoes, the combination of setting devices, of a movable anvil plate, a guide plate and a 45 work rest extending from said guide plate a portion thereof constructed to overlap the anvil plate during a part of the motion of the latter.

12. In a machine for operating on boots 50 and shoes, the combination with means for feeding the work, of a guide plate, a presser foot, and a hooked plate fast thereto and forming a pivot upon which said presser foot is mounted.

13. In an eyeleting machine, the combination with eyelet setting devices, of a guide plate, a presser foot, and a spring to which 55 said presser foot is pivotally attached.

In testimony whereof I have signed my 60 name to this specification in the presence of two subscribing witnesses.

ROBERT B. SMITH.
